UNITED STATES PATENT OFFICE

170,759

TOY SHOPPING CART OR SIMILAR ARTICLE

Herman Kesler, Jenkintown, Pa.

Application May 4, 1953, Serial No. 34,826

Term of patent 14 years

(Cl. D34—15)

To all whom it may concern:

Be it known that I, Herman Kesler, have invented a new, original, and ornamental Design for a Toy Shopping Cart or Similar Article, of which the following is a specification, reference being had to the accompanying drawing forming a part hereof:

The single figure is a perspective view of a toy shopping cart or similar article, showing my new design.

I claim:

The ornamental design for a toy shopping cart or similar article, substantially as shown.

HERMAN KESLER.
